UNITED STATES PATENT OFFICE.

EDWIN REYNOLDS, OF PROVIDENCE, RHODE ISLAND.

HAND-STAMP.

SPECIFICATION forming part of Letters Patent No. 446,587, dated February 17, 1891.

Application filed March 24, 1888. Serial No. 268,394. (No model.)

To all whom it may concern:

Be it known that I, EDWIN REYNOLDS, a citizen of the United States, residing at Providence, in the State of Rhode Island, have invented a new and useful Improvement in Hand-Stamp, of which the following is a specification.

My invention consists in an improved spring holder and handle for the rubber die and die-plate of a hand-stamp, as hereinafter set forth.

Figure 1 is a vertical section of the spring die-holder and the die-plate. Fig. 2 represents a section taken in the line $\alpha\alpha$ of Fig. 1, showing a top view of the spring die-holder and die-plate. Fig. 3 is a side elevation of the die-plate shown in Fig. 1. Fig. 4 is a side view showing a modification of the die-plate. Fig. 5 represents a top view of the die-plate, 20 the position of the handle and spring when turned to one side being shown by the dotted lines. Fig. 6 represents an end elevation showing the die-holder and spring-handle when in use.

25 In the accompanying drawings, A is the handle, which is secured centrally to the curved spring B, the said spring being attached to the handle by means of a screw s, or in any suitable manner, and provided at 30 its opposite ends with the holding notches or slots ff .

The die-plate C may be made of a piece of wood a , to the back of which is secured the metal plate b , the said plate being provided 35 with the inwardly-directed studs cc , which are struck up from the plate b , and are adapted to enter the notches ff of the holding-spring, and thus serve to prevent lateral movement. The ends ee of the holding-spring B at the 40 bottom of the openings ff are farther apart than the ends of the inwardly-directed studs cc , so that the spring B must be first inserted at one end under one of the studs c and then sprung under the opposite stud, and when so held a downward pressure upon the handle A 45 will tend to force the ends ee still farther under the studs cc on account of the flexure of the said spring, the distance between the ends ee at the bottom of the openings ff 50 being made less than the distance between the base of the studs cc , in order to provide for the proper yielding movement of the spring B.

The handle A can be readily removed from the die-plate by pressing endwise upon the holding-spring B, so as to bring the ends ee 55 of the said spring nearer to each other and cause them to pass between the inner ends of the studs cc of the plate b .

Instead of the wooden portion a of the die-plate C, an equivalent metal plate may be employed, the holding-plate b being soldered or otherwise attached thereto; or the plate b may itself form the die-plate to which the rubber die D is to be attached.

The operating-handle A for the holding-spring may be made in any desirable form, and need not in all cases be directly attached to the spring, but may be arranged in combination with intervening parts.

Instead of the studs c , formed by striking 70 up a portion of a sheet-metal plate, the said attaching-studs can be formed by a headed screw or nail, as shown in Fig. 4.

My invention, as above described, provides the desired flexibility between the die-plate 75 and its handle, whereby the rubber die D, which is attached to the plate a , can be made to fit squarely upon the surface to be printed, and it also provides a ready and convenient means for operating with a plurality of dies, 80 a single handle A being adapted for rapid attachment to and removal therefrom.

The holding-spring B, when constructed as above described and adapted for insertion under the spurs cc , is not liable to become 85 detached by continued use, the downward pressure upon the handle A serving to cause the yielding spring to spread farther under the opposite engaging studs, thus increasing the hold upon the same, and the peculiar lateral movement or twist of the spring is illustrated in Figs. 5 and 6, the normal position 90 of the handle A and spring B with reference to the die-plate C being shown by the full lines in Fig. 5, while the position of the handle and spring when in use and inclined, as in Fig. 6, so that the die D may rest fairly upon the surface to be printed, is shown by the dotted lines, the arms of the spring B being subjected to a twisting movement, which 95 causes a slight turning movement under the head of the holding-studs c , and this twisting movement, combined with the turning movement under the studs, as shown in Fig. 100.

5, constitutes the gist of my improvement, and by means of the turning freedom at the ends of the spring, as shown by the dotted lines in Fig. 5, the proper degree of flexibility 5 is obtained.

I claim as my invention—

The combination, with the flexible bow-spring provided with openings at its opposite ends and the handle attached to the middle 10 portion of the said spring, of a die-plate pro-

vided with the projecting studs, which are loosely held in the said openings of the spring, whereby the handle may be held to one side at an angle with the die-plate by causing the torsion of the spring, substantially as de- 15 scribed.

EDWIN REYNOLDS.
